UNITED STATES PATENT OFFICE.

ARCHIE D. STANDEFORD, OF KANSAS CITY, MISSOURI.

SHUTTER FOR MOVING-PICTURE MACHINES.

1,215,887.

Specification of Letters Patent. Patented Feb. 13, 1917.

Application filed October 3, 1914. Serial No. 864,780.

To all whom it may concern:

Be it known that I, ARCHIE D. STANDEFORD, a citizen of the United States, residing at Kansas City, in the county of Jackson and State of Missouri, have invented certain new and useful Improvements in Shutters for Moving-Picture Machines, of which the following is a specification.

My invention relates to improvements in shutters for moving picture machines, and the object of the invention is to provide a shutter having blades which may be expanded or contracted for the purpose of controlling the degree of light projected upon a screen, causing the moving pictures to be displayed more distinctly and with less strain on the eyes than heretofore, by eliminating the flicker occurring under the many different conditions of projection.

In order that said invention may be fully understood, reference will now be made to the accompanying drawings, in which:

Figure 1 is a broken front elevation of a moving picture machine provided with my invention.

Fig. 2 is a plan view of the same.

Fig. 3 is a cross section, enlarged, on line III—III of Fig. 2.

Fig. 4 is a longitudinal section, enlarged, on line IV—IV of Fig. 2.

Fig. 5 is a detail perspective view of a grooved sleeve employed in carrying out the invention.

Fig. 6 is a perspective view of a shifting bar constituting part of the invention.

Fig. 7 is a side elevation of a bushing adapted to fit into one end of the grooved sleeve.

Fig. 8 is a broken side elevation of one of the blades of the shutter.

Fig. 9 is a plan view of the part disclosed by Fig. 8.

Fig. 10 is a detail side elevation of a shifting collar for actuating the shifting bar disclosed by Fig. 6.

A designates a moving picture machine of any ordinary or preferred form provided with the customary projecting lens B, and the shutter shaft C.

1 designates the adjustable shutter constituting an important feature of the present invention.

Said shutter consists of a wide blade 2, and two comparatively narrow blades 3 and 3^a. The narrow blade 3 consists of a pair

of members 4 and 4^a, arranged to move in opposite directions to enlarge or contract said blade 3, as will hereinafter appear. The narrow blade 3^a, also consists of a pair of members 4^c and 4^b, arranged to move in opposite directions to enlarge or contract said blade 3^a.

Blade 2 is rigidly mounted at its reduced end upon a hub 5 provided with a longitudinal slot 6 and loosely mounted upon a sleeve 7, having a groove 8 extending longitudinally thereof. One end of the sleeve 7 is also provided with longitudinal slits 8^a and 9 to render it resilient, so that it may be made to firmly embrace a bushing 10 by a clamping member 11.

Bushing 10 fits into the counterbored end 8^b of the sleeve 7 and is firmly secured to the shaft C by any suitable means, such as a set-screw 12 passing through said bushing 75 into a longitudinal groove 13 in the shaft C, Fig. 4.

The members 4 and 4^b of the narrow blades 3 and 3^a are rigidly mounted at their reduced ends upon hubs 14 and 15 having 80 slots 16 and 17, respectively, extending obliquely in opposite directions, as disclosed by Fig. 2.

The members 4^a and 4^c of the narrow blades 3 and 3^a are rigidly mounted at their reduced ends upon hubs 18 and 19 provided with slots 20 and 21, respectively, extending obliquely in opposite directions.

All of the blade hubs are loosely mounted upon the grooved sleeve 7, but secured from 90 moving longitudinally of said sleeve by collars 22 and 23 provided with set-screws 24 and 25, respectively, whereby they are firmly secured to the sleeve 7, Fig. 4.

26 designates a shifting bar slidably 95 mounted in the groove 8 of the sleeve 7 and provided with upwardly-extending lugs 27, 28, 29, 30, 31, 32; the five latter projecting upwardly into the slots 6, 16, 17, 21 and 20, respectively, Figs. 2 and 4, to cause the blade 100 hubs to rotate with the sleeve 7 and also to adjust said blade hubs axially, as will hereinafter appear.

The lug 27 projects upwardly into an opening 33 in a shifting collar 34 slidably 105 mounted upon the sleeve 7 to move the shifting bar 26 freely, longitudinally, for the purpose of adjusting the members of the blades 3 and 3^a, axially, as above-referred to.

The collar 34 is adjusted longitudinally 110

of the sleeve 7 by a lever 27, which in turn is adjusted by a screw 38, threaded into an arm 39, secured to the bearing D of the shaft C.

5 In practice, the blade 2 is adjusted axially to obstruct the light projected through the lens B at each movement of the film, by loosening the clamping member 11, which permits the sleeve 7 and all the parts carried thereby to be rotated upon the shaft C and the bushing 10 until proper adjustment is effected, when the clamping member 11 is again tightened. After the wide blade 2 has been properly adjusted the narrow 15 blades 3 and 3^a may be enlarged to shut off superfluous light from bright pictures by shifting the collar 34 to the left, or toward the shaft bearing D. This movement of the collar 34 shifts the bar 26 longitudinally, 20 causing its lugs 29 to 32, inclusive, to move through the oblique slots 16, 17, 21 and 20, respectively, and thereby enlarge the blades 3 and 3^a. When a dark picture requiring more light is to be exposed, the blades 3 25 and 3^a are contracted by shifting the collar 34 to the right, thereby causing the lugs 29 to 32 to axially shift the respective hubs through which they slide, in a reverse direction. This enlarging and contracting of the 30 blades 3 and 3^a may be accomplished through proper manipulation of the screw 38 while pictures are being projected upon a screen, at which time the operator is better enabled to judge the degree of light required for different pictures. From the foregoing it will 35 be readily understood, that the proper degree of light for displaying the moving pictures to the best advantage can be readily obtained at will. As the slot 6 in the hub 40 of the wide blade 2 is straight instead of being arranged obliquely, as are the slots in the companion hubs, the position of said blade 2 upon the sleeve 7 is not affected by the movement of the lug 28 from one end 45 of slot 6 to the other.

As the area of the blade 2 is not affected by the enlargement and expansion of the blades 3 and 3^a, it is obvious that the blade members 4^a and 4^b must travel twice the distance of the blade members 4 and 4^b to maintain equal spaces between the blades 2, 3 and 3^a, consequently the angle of the slots 20 and 21 is twice as great as the angle of the slots 16 and 17.

55 While I have shown and described a three blade shutter in the present instance, it is to be understood that the number of blades may be increased or diminished as desired, and that other changes falling within the 60 spirit and scope of the claims can be made.

Having thus described my invention, what

I claim and desire to secure by Letters Patent, is:

1. A shutter adapted to be mounted upon a shaft and having a blade consisting of a 65 plurality of members capable of axial adjustment, an independent hub for each member, each hub having an oblique slot, and means extending into said slots to adjust the hubs axially. 70

2. A shutter adapted to be mounted upon a shaft and having a blade consisting of a 75 plurality of members capable of axial adjustment, independent hubs for said members having oblique slots extending in different directions, and means extending into said slots to simultaneously adjust the hubs axially. 75

3. A shutter adapted to be mounted upon a shaft and having a blade consisting of a 80 plurality of members capable of axial adjustment, independent hubs for said members having oblique slots, lugs extending into said slots, and means for shifting said lugs to adjust the hubs axially. 85

4. A shutter adapted to be mounted upon a shaft and having a blade consisting of a 90 plurality of members capable of axial adjustment, independent hubs for said members, a bar having means engaging said hubs to adjust the same axially, and means for actuating said bar. 90

5. A shutter adapted to be mounted upon a shaft and having a blade consisting of a 95 plurality of members capable of axial adjustment, independent hubs for said members, a bar having means engaging said hubs to adjust the same axially, and a lever for actuating said bar. 95

6. A shutter adapted to be mounted upon 100 a shaft and having a blade consisting of a plurality of members capable of axial adjustment, independent hubs for said members, a bar having means engaging said hubs to adjust the same axially, and a grooved 105 sleeve in which said bar is mounted.

7. In combination with a rotary shaft of a moving picture machine, a bushing mounted upon said shaft, a sleeve mounted upon the shaft and said bushing and having a 110 longitudinal slot, a shutter mounted upon said sleeve and embodying a blade having a plurality of members capable of axial adjustment, and a shiftable bar slidable in the slotted sleeve and engaging the members of 115 said blade to adjust them axially.

In testimony whereof I affix my signature in the presence of two witnesses:

ARCHIE D. STANDEFORD.

Witnesses:

F. G. FISCHER,

L. J. FISCHER.
